UNITED STATES PATENT OFFICE

99,424

DESIGN FOR A COLLAPSIBLE TUBE CONTAINER

Simon de Vaulchier, New York, N. Y., assignor to
Pinaud Incorporated, New York, N. Y., a corporation of New York

Application May 14, 1935, Serial No. 56,824

Term of patent 14 years

To all whom it may concern:

Be it known that I, Simon de Vaulchier, a citizen of the French Republic, residing at the Vanderbilt Hotel, Park Avenue and 34th Street, in the county of New York and State of New York, have invented a new, original, and ornamental Design for a Collapsible Tube Container, of which the following is a specification, reference being had to the accompanying drawing, forming a part thereof.

In the drawing:

Figure 1 is a top plan view of a bottle showing my new design;

Figure 2 is a front elevation view thereof;

Figure 3 is a side elevation view thereof.

I claim:

The ornamental design for a collapsible tube container as shown.

Dated, May 10th, 1935.

SIMON DE VAULCHIER.
